UNITED STATES PATENT OFFICE.

JAMES BEARD, OF PASADENA, CALIFORNIA.

HOT-AIR GAS FURNACE.

Application filed July 5, 1924. Serial No. 724,460.

This invention relates to hot air furnaces in which illuminating gas is utilized for fuel.

The object of the invention is to provide a hot air furnace having a radiator enclosed 5 within an inner casing surrounded by an outer casing, in which air is heated by being brought into contact with the heating surface of the radiator and inner casing.

The object is accomplished by the dis- 10 closure of the invention herein set forth by the following description of the accompanying drawings in which the construction and advantages are clearly set forth and the novel features thereof pointed out in the ap- 15 pended claims.

Referring to the drawings:

Figure 1 is a horizontal section taken on the line 1—1 of Fig. 2,

Fig. 2 is a vertical section taken substan- 20 tially on the line 2—2 of Fig. 1,

Fig. 3 is a section taken on the line 3—3 of Fig. 2, and

Fig. 4 is a fragmentary, horizontal sec- 25 tion taken on the same plane as Fig. 2, showing a modification of the upper portion of the furnace.

Referring by numerals to the accompanying drawings, 10 designates an outer casing which surrounds an inner casing 12, the up- 30 per portion of the casings 10 and 12 being joined by a top 11. The casings 10 and 12 are provided with doors 13 and 14.

A radiator, generally designated at 15, is positioned within the casing 12 and is sup- 35 ported by brackets 16 which are fastened to the casing and extend under the radiator. The casings 10 and 12 are formed of thin sheet metal and rest on a base or floor 17.

The radiator is composed of a series of 40 parallel compartments 18, 19, 20 and 21, which are connected by passages 22, 23 and 24. A compartment 26, which is of larger size than the compartments 18 to 21 in- 45 clusive, is connected to the compartment 18 by a passage 27, and is provided with a baffle plate 28 and a bottom 29 having an opening 30 through which extends a chimney 31 of a gas heater 32. A vent chamber 33 is connected to the compartment 21 by a conduit 34 and is provided with a pipe or stack 35.

The top portion of the casing 12 is entire- 50 ly enclosed by a cover 36 from which lead hot air pipes 37.

Referring to Fig. 1, it will be seen that the 55 radiator is of zig-zag formation, there being air circulating passages 38, 39, 40 and 41 be-

tween the compartments 18, 19, 20, 21 and 26; and as the radiator is smaller than the casing 12, additional air circulating space 42 is provided between the interior of the 60 casing 10 and the exterior of the radiator 15.

Upright plates 43 and 44 support an inclined baffle plate 45. An opening 46 is provided in the casing 10 below the bottom of the radiator while oppositely disposed open- 65 ings 47 are formed in the casing 12 adjacent the heater 32. The heater 32 consists chiefly of a burner 48, a cylinder 49, a sup- 70 porting stand 50 and the chimney 31, as clearly shown in Fig. 2. Gas is supplied to 75 the burner by a pipe 51 controlled by a valve 52.

The fire is started by opening the doors 13 and 14 and the valve 52, then igniting the 80 gas passing out of the burner 48 of the 75 heater 32, after which the doors are closed.

The air to be heated by the radiator and supplied to the heater enters the furnace through the opening 46, a portion of which is deflected by the baffle plate 45, and brought 85 into contact with and preheated by the sur- 90 face of the vent chamber 33, and then mixed with the air passing through the opening 46 in the end wall of the outer casing 10 be- 95 tween the plates 43 and 44. The air is then 95 passed between the casings 10 and 12, as indicated by the arrows 53, into the inner casing 12 through the oppositely disposed open- 100 90 ings 47 at which time it is again pre- heated by the external surface of the casing 10 adjacent the radiator.

The heat and products of combustion generated by the burner pass through the chimney 31 into the lower portion of the compartment 26 around the baffle plate 28, then suc- 105 cessively through the compartments 18, 19, 20 and 21 and passages 27, 22, 23 and 24 into the stack 35 via conduit 34 and vent chamber 33, thus heating the radiator.

The external heating surface of the radi- 110 ator will cause an upward current of air through the passages 38 to 41 (between the compartments 18, 19, 20, 21 and 26) and space 42 between the radiator and casing 10, thence into the distributing pipes 37.

From the construction it will be seen that the furnace, while simple in construction, is very efficient as the zig-zag formation of the radiator provides considerable heating area to the preheated air, and that the heat and production of combustion from the heater pass directly through the radiation without

mixing with the heated air entering the pipes 37.

The furnace is installed in the basement of a building, the pipes 37 being carried to 5 different parts of the building while the stack 35 is connected to the chimney or extends through the roof in the usual manner.

In the form shown in Fig. 4, instead of using a plurality of pipes for transferring 10 heat to different parts of the building as referred to, a single pipe or conduit 54 of sufficient size is centrally positioned in the cover portion 36 and extends through the floor 55 of the basement into the room above, 15 the construction of the furnace being the same in other respects as shown in Figs. 1, 2 and 3.

I claim as my invention:—

1. A hot air gas furnace comprising an 20 outer casing, an inner casing within said outer casing, said inner and outer casing being connected at their upper ends, a radiator within said inner casing comprising a plurality of vertically mounted compartments in spaced relation, each of said compartments being of rectangular shape in vertical and horizontal cross section and joined by oppositely disposed passages extending from top to bottom, a vent chamber connected to the outer side of said inner casing, 25 a conduit connecting said vent chamber and a compartment of said radiator adjacent said vent chamber, a gas heater within said inner casing having a chimney extending

through an opening in the compartment of 35 said radiator, directly above said heater, and a cover over said inner casing having openings therein and pipes leading therefrom.

2. A hot air furnace comprising a radiator consisting of a plurality of vertically 40 mounted compartments in spaced relation connected by oppositely disposed passages extending from top to bottom forming a horizontal zig zag air passage, a heater having a chimney extending through an opening 45 in the bottom of the forward compartment of said radiator, an inner casing enclosing said radiator and a heater having oppositely disposed openings therein, below said radiator and adjacent said heater, a cover extending over said inner casing having openings therein and pipes leading from said openings adapted to receive the air heated by said radiator, a vent chamber mounted on the outer side of said inner casing, a 50 conduit forming a passage between the rear compartment of said radiator and said vent chamber, an outer casing surrounding said inner casing and having an air inlet therein below and adjacent said vent chamber, said outer and inner casings being joined at their 55 upper ends and a stack extending upwardly from said vent chamber through an opening in the top of said outer casing.

In testimony whereof I have signed my 60 name to this specification.

JAMES BEARD.
